UNITED STATES PATENT OFFICE.

BYRON SNYDER, OF CLINTON, WISCONSIN.

ELEVATED CARRIER.

No. 891,875.

Specification of Letters Patent. Patented June 30, 1908.

Application filed September 14, 1907. Serial No. 392,943.

To all whom it may concern:

Be it known that I, BYRON SNYDER, a citizen of the United States, residing at Clinton, Rock county, Wisconsin, have invented certain new and useful Improvements in Elevated Carriers; and I do hereby declare the following to be a full, clear, and exact description of the invention, such as will enable others skilled in the art to which it applies to make and use the same.

This invention relates to certain improvements in elevated carriers; and the objects and nature of the invention will be readily understood by those skilled in the art in the light of the following explanation of the structures illustrated in the accompanying drawing of what I now consider my preferred construction from among other arrangements and structures within the spirit and scope of my invention.

My invention consists in certain novel features in construction and in combinations and arrangements of parts as more fully and particularly set forth hereinafter:

Referring to the accompanying drawings:—Figure 1 is a perspective view of the carrier showing the same locked to the cable track by the brake. Fig. 2, is an elevation looking in the opposite direction and showing the brake in its normal inoperative position. Fig. 3, is an end view of the box and a portion of the frame, dotted lines indicating the position of the box when held by the stop device about midway between carrying position and completely inverted or dumping position. Fig. 4, is a detail perspective view of the frame of one of the wheeled hangers, the wheel and guard being removed. Fig. 5, is a vertical central section through the upper portion of a wheeled hanger.

In the drawings, 1, is the elevated track which in the present instance, is shown formed by a cable supported by any suitable means, and is usually provided with any suitable trip projection such as 2, clipped or otherwise secured thereto over the stop or location where it is desired that the carrier shall be dumped to deposit the load of litter or other material transported by the carrier from a barn or other building or location.

3, is the litter or dump box which can be of any suitable or desirable construction with an open top. In the present instance, I show trunions or shaft stubs 4, rigid with 55 and projecting from the box ends and suit-

ably affixed thereto. At one end, the box is provided with the fixed curved or segmental keeper 5, at its crown or elevated portion having the locking notch or recess 6, to receive the locking bolt or latch. 60

A suitable frame is provided for carrying the box. In the specific example illustrated, I show a depending or inverted U-shaped frame consisting of the longitudinal top bar 7, and the two parallel legs 8, rigid with and 65 depending from the ends of the top bar. At their lower portions the legs 8, are provided with journal boxes 9, in which the shaft stubs 4, of the box are mounted and by which the box is supported. 70

The box is held in carrying position by a horizontally disposed vertically swinging latch or bolt 10, at its outer end pivoted to the side face of one of the legs 8 by a transverse bolt or rivet 11, and from thence extending inwardly over the keeper 5 and at its inner end having a short depending lug or bolt 12, to enter the notch 6 of the keeper and thereby hold the box in upright carrying position and against tilting. 75

The latch is lifted from the keeper to permit the box to dump by a system of links and levers comprising the vertically disposed trip lever 13 arranged about midway the length of the frame top bar 7, and extending 80 above and below said bar and arranged beside the same and between its upper and lower ends fulcrumed to said bar by a transverse bolt or rivet 14. The upper end of this lever is bent into a horizontal position a distance above the top bar 7 to form the trip 85 engaging end of portion 15. A vertically disposed lever 16, is arranged beside and longitudinally of the frame bar 8 carrying the latch, and between its ends is fulcrumed to 90 said bar by a transverse bolt or rivet 17, and the upper end of this lever 16 is operatively connected to the lower end of the trip lever by a wire or rod link 18 arranged in practically a horizontal position and preferably 95 having its opposite ends bent laterally about at right angles and inserted through perforations through the lever ends and secured loosely therein by cotter pins 19. The lower end of the lever 16, is connected to the free 100 end of the latch by a pull rod 20 and link 21, loosely connecting the parts.

From the foregoing description it will be readily understood that as the frame moves along the track, the end 15 of the trip lever 110

will engage the trip 2, and be rocked thereby, and the upright lever 16 will be hence rocked to lift the latch, and permit the box to dump.

In the specific example illustrated, I show 5 means whereby the box can be held in position about midway between carrying and reversed positions so that access can be easily had to the bottom and interior of the box for cleaning, after the box has been in use, or the 10 box can be kept in this position when not in use to prevent the box from collecting water and snow. The means illustrated for this purpose consists of a swinging or pivoted button or latch 22, arranged at the side face 15 of the frame leg 8, preferably the leg not carrying the latch, and pivoted thereto by a transverse bolt or rivet 23, so that the button can swing to a vertical position at the face of the leg or can be swung into a horizontal 20 position projecting inwardly into the path of movement of a bracket or socket piece 24, fixed at the exterior of the adjacent end of the box and near one corner thereof. When the button is swung down to operative position 25 and the box dumps, the socket piece will engage the projecting end of the button and hold the box in position on one side. The socket piece merely forms a projecting stop to engage the end of the button and can be 30 of any suitable and desirable form, and in fact the button can be of any suitable or desirable form to constitute a stop, and one of these stops is adjustable into and out of the path of the other.

35 The box and its supporting frame are, in the specific example illustrated, carried by two wheeled hangers arranged at the opposite end portions of the top bar of the frame. Each hanger is pivotally joined to the frame 40 bar to permit independent horizontal oscillation of the hanger, and comprises a frame, a grooved wheel, and a guard device to prevent derailment of the wheel and yet permit the wheel to freely pass from and to the cable 45 on entering and leaving switches or the like.

In the specific example illustrated, the frame consists of a strong metal vertical upright or frame piece 25, having a horizontally elongated loop frame 26 arranged at a side 50 face of the upper end of the upright and rigid therewith and fixed thereto at the central portion of the length of the loop frame. The grooved wheel 27 is mounted in and encircled by this loop frame with the wheel projecting about an equal distance above and below the loop. The wheel is preferably deeply grooved so as to follow the cable and curves of the switches or other track ways and cause the wheel and hanger to horizontally rock in following the curves of the trackway.

55 28, is a beveled guard or guide formed on the side face of the upright just below the inner edge of the wheel to guide the cable 60 into the groove. Below the wheel, the up-

right is formed at its lower end with a strong horizontal ear 29 extending beneath the lower edge of the top bar of the box frame, and 30 is an ear parallel with the ear 29, and extending across the top edge of said top bar. 70 The hanger is pivotally joined to said top bar by a vertical coupling bolt 31, passed down through said ears and through the longitudinal side flanges of the top bar. The vertical inner face of the upright of the hanger 75 between said ears 29, 30, and at the side face of the top bar is beveled off transversely in opposite directions, at 32, from the longitudinal center of the upright, so that the hanger can oscillate in either direction on the 80 pivot or coupling bolt 31 as a center, as the wheel follows the curvatures of the trackway.

To prevent derailment of the hanger wheels, I provide each hanger with a guard comprising a pair of swingable pendants arranged on the opposite side of the wheel from the hanger frame upright 25. The pendants are arranged at the opposite end portions of the loop frame 26, and each consists of a freely hanging metal bar 33, at its upper end 90 carried by a transverse bolt or rivet passing loosely through the bar and through the forked end of a bracket 34 fixed to and depending from the end portion of the loop frame. The brackets 34 are rigidly secured 95 to the outer length or portion of the loop frame and are usually forked at their lower ends or otherwise arranged to bring the guard bars 33, as close to the face of the wheel as possible and yet permit free swing of the 100 bars. The guard bars depend into engagement with a spring 35, at its central portion secured to the top ear 30 of the hanger frame with its ends extending in opposite directions and springing and convexed upwardly 105 so as to yieldingly engage the lower ends of the guard bars and yieldingly hold the same in their normal vertical guarding positions, and yet so that said bars can freely swing in either direction when engaging a switch or 110 other obstruction. The spring lightly engages the ends of the guard bars so that when the hanger passes a switch the bars can swing back to their normal positions.

It is often desirable to lock or hold the carrier at some particular point or location against movement on the track, and I have hence provided a very simple and efficient brake device which can be easily and quickly operated and which can be very economically constructed and is very durable. The brake mechanism consists of a vertically swinging brake shoe or brake lever 36 arranged at the side face of the top bar of the box frame and fulcrumed thereto by a transverse bolt or rivet 37 at about the center of the length of said top bar, that is about midway between the two hanger wheels. The upper end of this lever 36, is bent laterally or at right angles to form a brake shoe 38 ar- 125 130

ranged between the track cable and the top edge of the frame top bar, and the length of the lever between its fulcrum and the brake shoe is greater than the normal distance between the cable track and frame top bar, so that when the lever is in the vertical braking position its shoe presses upwardly against the cable midway between the hanger wheels elevating the cable between said wheels or 10 engaging the same with sufficient force to prevent movement of the carrier along the track. The brake lever is normally in its lowered position swung down with its brake shoe resting on the top edge of the frame top bar. Suitable means are provided to operate the brake lever and lock the same in braking position. For instance, I show a curved or bowed horizontally disposed operating bar, lever or handle 39, arranged longitudinally of the carrier frame and at its ends projecting beyond the same forming the projecting end hand or finger holds 40, beyond the legs of the carrier frame. At about the center of its length, this bar 39 crosses and is pivotally joined, at 41, to the brake lever at a point between its fulcrum and the brake shoe, whereby the brake lever can be swung vertically in either direction by longitudinal movement of the bar 39 from 25 either end of the carrier frame. Guide loops 42, are provided for the opposite ends of the bar 39, and these loops are rigidly secured to the side faces of the frame legs. The bar 39 can be locked against longitudinal movement to hold the brake lever in vertical braking position by notches 43 in the lower edge thereof at either or both ends of the bar to receive the lower end wall of either or both guide loops. The brake lever and its operating bar 39 are preferably arranged on the opposite side of the carrier frame from the trip lever and connections therefrom to operate the box-latch.

It is evident that various changes and modifications might be resorted to, that elements might be omitted or constructions added, without departing from the spirit and scope of my invention, and hence I do not wish to limit myself to the exact constructions disclosed.

What I claim and desire to secure by Letters Patent of the United States is:—

1. An elevated carrier comprising a carrier frame, a dump box mounted therein to assume the upright carrying position and the completely inverted dumping position, means for locking and releasing the dump box for dumping the same, and a stop device between the box and frame whereby the dump box can be held in an abnormal intermediate position, substantially as described.

2. An elevated carrier comprising a carrier frame having depending legs, a dump box mounted in said frame and arranged be-

tween said legs to assume the upright carrying position and the completely inverted dumping position, means for holding the box in carrying position and for dumping the same, a stop arranged on the exterior of an end of the box, and a stop arranged on the adjacent leg and adapted to coöperate with said first mentioned stop in holding the box in an abnormal intermediate position for cleansing or other purposes.

3. An elevated carrier comprising a carrier frame, a dump box mounted therein to assume the upright carrying position and the completely inverted dumped position, latch mechanism for said box, a stop carried by and projecting beyond an end of the box, and a coöoperating stop carried by the frame, one of said stops being movable to and from the path of movement of the other stop, whereby said box can be stopped in an abnormal intermediate position.

4. An elevated carrier comprising a carrier frame, a dump box mounted therein and provided with an end keeper, a latch carried by the frame to coöperate with said keeper in locking the box, a vertically disposed lever fulcrumed between its ends to the frame, a loose pull connection from the lower end of said lever to said latch, a vertically disposed trip lever between its ends fulcrumed to the frame, and a rod horizontally disposed between the lower end of the trip lever and the upper end of said first mentioned lever and at its ends pivotally joined thereto.

5. An elevated carrier comprising a U-shaped carrier frame, a dump box carried by and arranged between the legs of said frame, a vertically swinging latch to lock said box and pivoted to one of said legs, a lever longitudinally of and beside said leg and between its ends fulcrumed thereto, a loose pull connection between the lower end of said lever and the free end of said latch, a vertically disposed trip lever arranged beside an intermediate portion of the top bar of said frame and fulcrumed between its ends thereto and projecting above and below said bar, and a horizontally disposed connection between the lower end of the trip lever and the upper end of said first mentioned lever.

6. An elevated carrier comprising a carrier frame, a box, and a wheeled hanger comprising an upright at its lower end confined to the frame and at its upper end provided and rigid with a side horizontally elongated open loop frame, a guard depending therefrom, and a grooved wheel encircled by and mounted in said loop frame.

7. An elevated carrier comprising a carrier frame, a box carried thereby, and a wheeled hanger comprising an upright arranged beside the top bar of the frame and having lateral ears extending above and below the same and pivotally joined thereto, the inner ver-

tical face of the upright between said ears being oppositely and transversely beveled, substantially as described.

8. An elevated carrier comprising a carrier frame provided with a wheeled hanger extending down beside the frame and pivotally joined thereto to oscillate horizontally independently thereof, the face of the hanger frame beside the carrier frame being oppositely and transversely inclined or beveled, substantially as described.

9. An elevated carrier comprising a frame having a wheeled carrier provided with a guard consisting of spaced depending independently swingable members at their upper ends pivoted to the frame.

10. An elevated carrier comprising a carrier frame provided with a wheeled hanger having a guard comprising a depending swingable bar, and a spring adapted to yieldingly engage said bar and normally hold the same in normal guarding position.

11. An elevated carrier comprising a carrier frame provided with a wheeled hanger having swingable guard pendants pivoted at their upper ends, and a spring having upwardly springing ends adapted to engage the lower ends of said pendants and normally hold the same in guarding position.

12. An elevated carrier comprising a carrier frame provided with wheeled hangers, and a brake mechanism comprising a swinging brake lever, and operating means therefor for throwing the same into and out of operative engagement with the track cable at a point between the hangers.

13. An elevated carrier comprising a carrier frame provided with a wheeled support adapted to travel on a cable track, and a brake mechanism comprising a vertically swinging brake lever fulcrumed to the frame and provided with a brake shoe to engage and press upwardly against said cable, and an operating bar arranged longitudinally of the frame and pivotally joined to said lever to swing the same to and from locking position.

14. An elevated carrier comprising a car-

rier frame having a top bar and depending legs, a dump box carried thereby, wheeled supports therefor adapted to travel on a cable track, a brake lever fulcrumed to said top bar and at its upper end having a brake shoe to engage said cable, means for swinging said lever to and from braking position, and means for detachably locking the same in braking position.

15. An elevated carrier comprising a carrier frame having a wheeled support adapted to travel on a cable track, a vertically swinging brake lever fulcrumed to said frame and at its upper end having a shoe to engage said cable, a manually operated longitudinally movable bar arranged longitudinally of the frame and at its ends projecting beyond the same and intermediate its length pivotally joined to said lever, and guides carried by the frame through which said bar can slide and move vertically, said bar being notched to engage a guide for locking the lever in braking position.

16. An elevated carrier comprising a carrier frame having a longitudinal top bar, a dump box, latch mechanism therefor, hangers for said frame, each hanger frame extending down beside said bar and having lateral ears above and below said bar, and a vertical pivot bolt passing through said ears and the bar.

17. In combination, in an elevated carrier, a frame, a dump box carried thereby and provided with latch mechanism, a vertically disposed supporting hanger at its upper portion provided with a supporting wheel to travel on an elevated track and at its lower portion provided with horizontal ears between which a portion of said frame rests, and means confining said portion of the frame between said ears, substantially as described.

In testimony whereof I affix my signature, in presence of two witnesses.

BYRON SNYDER.
